UNITED STATES PATENT OFFICE.

FRED LUMMER, OF MILWAUKEE, WISCONSIN.

CLAMP-BOLT LOCK.

Application filed June 30, 1922. Serial No. 571,847.

To all whom it may concern:

Be it known that I, FRED LUMMER, a citizen of the United States, and resident of Milwaukee, in the county of Milwaukee and 5 State of Wisconsin, have invented new and useful Improvements in Clamp-Bolt Locks, of which the following is a description, reference being had to the accompanying drawing, which is a part of this specification.

10 This invention relates to certain new and useful improvements in clamp bolt locks.

In that style of clamp employed for attaching motors to row boats and the like considerable difficulty has been experienced 15 in preventing loosening of the clamping means by reason of the motor vibration causing retrograde movement of the clamp bolt. As a result many motors have been lost and if salvaged at all, done so only at considerable expense.

Therefore, having this in mind it is one of the objects of my invention to provide means engageable with the clamp bolt whereby the same is positively held against 25 retrograde movement and at the same time may be readily released to permit the unscrewing of the bolt.

It is another object of this invention to provide a clamp bolt lock which is adapted 30 for use not only in connection with that type of clamp employed for attaching a portable motor to a boat but may be employed in any type of clamp as for instance the C-clamp commonly utilized in securing 35 work to a drill press or lathe where it is especially desirable to firmly secure the work against shifting by the vibration of the machine.

It is a further object of my invention to 40 provide a device of the character described in which the locking member is at all times yieldably urged to engage in the slots or recesses of the clamping bolt and which may be readily moved and held against the action 45 of its spring to permit the free rotation of the clamp bolt in either direction.

A still further object of this invention resides in the provision of a device of the character described which may be readily 50 embodied in any type of clamp construction or may be employed where it is desired to prevent retrograde movement of a bolt member.

With the above and other objects in view 55 which will appear as the description proceeds, my invention resides in the novel con-

struction, combination and arrangement of parts substantially as hereinafter described and more particularly defined by the appended claim, it being understood that such changes in the precise embodiment of the herein disclosed invention may be made as come within the scope of the claim. 60

In the accompanying drawing, I have illustrated one complete example of the 65 physical embodiment of my invention constructed according to the best mode I have so far devised for the practical application of the principles thereof, and in which:

Figure 1 is a side view of that type of 70 clamp more especially designed for attaching a portable motor to a boat, a portion of the clamp being broken away and in section,

Figure 2 is an enlarged fragmentary view taken through Figure 1 on the plane of the 75 line 2—2, and

Figure 3 is a view similar to Figure 2 illustrating a slightly modified construction wherein the locking plunger is retained in proper alinement by reason of its shape. 80

Referring now more particularly to the accompanying drawing, the numeral 5 designates the rear end wall of a boat to which a portable motor, not shown, is to be secured by one or more clamps 6, one arm 7 of 85 which has a threaded bore 8 in which is secured a screw clamping bolt 9, the inner end of which carries a cap 10 for engagement with the wall 5 to secure the same firmly against the other arm 11 of the clamp. 90

The outer end of bolt 9 is provided with a winged part 12 or the like for convenience in rotating the same and the shank of the bolt has one or more longitudinally extending slots 13 one wall 14 of which is 95 tangentially arranged with respect to an imaginary circle having the axis of the bolt 9 as its center and the other wall 15 of which forms a continuation of an imaginary line passing through the axis of the bolt, the 100 wall 15 being on the far side of the slot when the bolt is being unscrewed.

The outer end 16 of the arm 7 is longitudinally bored, as at 17, transversely of bore 8 and communicating therewith, the outer end thereof being counter-bored or enlarged, as at 18, and closed by a removable cap member 19. The cap member 19 is centrally bored, as at 20, and has a plunger 21 projected therethrough and through bore 17 to permit engagement of its inner end 22 in slot 13. 110

The plunger is yieldably urged to engage its inner end with the bolt at all times by a spring 23 coiled about the plunger within counter-bore 18 and having one end 5 engaging against the inner face of the cap member and its other end engaging against a collar 24 fixed to the plunger. End 22 of the plunger is shaped to fit slot 13 so that when engaged therein wall 15 cooperates with the side of the plunger end engaging the same to positively lock the bolt against retrograde movement, and at the same time, permit its rotation in the other direction by reason of the inclined face 14 10 of the slot acting as a cam on the inclined wall of the plunger end.

It is desirable to retain the end 22 of the plunger in proper alignment at all times to prevent its being positioned transversely 20 of the slot and thus rendered inoperative, and in Figure 3 I accomplish this purpose by constructing bore 17 rectangular in cross section and shaping the inner end of the plunger to fit. In figure 2 this end is accomplished by a pin 25 which is carried by 25 the outer portion of the plunger and is engageable in a slot or recess 26 communicat-

ing with a bore of the cap member. Pin 25 not only holds the plunger in proper alignment but permits the same to be rendered 30 inoperative by pulling the plunger outwardly against the force of its spring and then rotating the same to disalign its pin with recess 26, as will be readily apparent. To permit the ready manipulation of the 35 plunger a cap or end 27 is secured to its outer end.

What I claim as my invention:

In a bolt lock, a bolt provided with longitudinally extending slots, a transversely disposed spring pressed plunger adapted to engage said slots to prevent retrograde movement of the bolt, a pin carried by the plunger adapted to cooperate with a slot in the member through which the bolt is 45 threaded to restrain the plunger from rotation, and a cap on the outer end of the plunger, said plunger being held out of engagement with the bolt by moving said cap outwardly to disengage the pin from its slot 50 and then partially rotating the cap to disalign said pin and slot.

In testimony whereof I affix my signature.

FRED LUMMER.
